(57) **CLAIM**

The ornamental design for a medical lab coat, as shown and described.

DESCRIPTION

FIG. 1 is a front elevational view of the medical lab coat of the present invention;

FIG. 2 is a rear elevational view of the medical lab coat of FIG. 1;

FIG. 3 is a left side elevational view of the medical lab coat of FIG. 1;

FIG. 4 is a right side elevational view of the medical lab coat of FIG. 1;

FIG. 5 is a top plan view of the medical lab coat of FIG. 1;

FIG. 6 is a bottom plan view of the medical lab coat of FIG. 1; and,

FIG. 7 is a rear elevational view in an alternate position (jacket closed) of the medical lab coat of FIG. 1.

The broken lines showing of a reflex hammer in FIGS. 1, 4, 5 and 6 are for illustrative purposes only and form no part of the claimed design. The broken lines elsewhere in the figures represents stitching and is part of the claimed design.
